UNITED STATES PATENT OFFICE.

JOSEPH R. McGARRITY, OF IRVINGTON, NEW JERSEY.

DESIGN FOR AN INKSTAND OR SIMILAR ARTICLE.

Application filed October 15, 1928. Serial No. 28,498. Term of patent 3½ years.

To all whom it may concern:

Be it known that I, JOSEPH R. McGARRITY, a citizen of the United States, and a resident of Irvington, in the county of Essex and State of New Jersey, have invented a new, original, and ornamental Design for Inkstand or Similar Article, of which the following is a specification, reference being had to the accompanying drawing, forming part thereof.

Fig. 1 is a top plan view of an inkstand or similar article showing my new design.

I claim:

The ornamental design for an inkstand or similar article, as shown.

JOSEPH R. McGARRITY.
